UNITED STATES PATENT OFFICE.

AUGUST KAZENMAIER AND EUGEN BAUER, OF STUTTGART, GERMANY, ASSIGNORS, BY MESNE ASSIGNMENTS, TO AMERICAN BOSCH MAGNETO CORPORATION, OF NEW YORK, N. Y., A CORPORATION OF NEW YORK.

STARTING SYSTEM FOR ENGINES.

1,312,991.

Specification of Letters Patent. Patented Aug. 12, 1919.

Application filed February 12, 1916. Serial No. 78,053.

To all whom it may concern:

Be it known that we, AUGUST KAZEN-
MAIER and EUGEN BAUER, both subjects of
the Emperor of Germany, residing at and
5 whose postoffice addresses are, respectively,
Pfeifferstrasse 4 and Hirschstrasse 37, in
Stuttgart, Germany, have invented certain
new and useful Improvements in Starting
Systems for Engines; and we do hereby de-
clare the following to be a full, clear, and
10 exact description of the invention, such as
will enable others skilled in the art to which
it appertains to make and use the same.

In motor starting systems for engines,
15 wherein speed reducing gearing of compara-
tively large ratio is generally used, there is
considerable back lash or play between the
motor and the engine, so that upon connect-
ing the source of power supply to the start-
20 ing motor, the absence of load in the initial
period in which the play is taken up results
in the fact that the motor starts with a rush,
especially since a series electric motor or
other motor having the same characteristic
25 high starting torque is used. The speed de-
veloped in this initial period is such that
when the play is taken up, the momentum
of the parts then in rotation, together with
the starting torque of the motor, is suddenly
30 applied to the engine, with the result that
severe strains may be developed in the ap-
paratus and a noisy and unsatisfactory op-
eration necessarily ensues. This is particu-
larly true if the gearing between the motor
35 and engine includes an over-running clutch
to automatically disengage them at the
proper time.

Our invention overcomes the objections
due to the rush of the motor in the initial
40 starting period and the sudden application
of an excessive starting torque to the engine
when the play has been taken up, and we do
this by supplying in the initial starting pe-
riod an amount of power sufficient to turn
45 the motor at slow speed and develop the
small torque required for overcoming the
resistance encountered in taking up the play
in the gearing, but not sufficient to start the
engine from rest, and then increasing the
50 supply of power to the full value necessary
to start the engine from rest. The rotating
members of the over-running clutch are
connected in this initial period, or previous
thereto, so that the play in the clutch also is

entirely taken up before the motor starts to 55
develop the increased power. In case the
starting system is applied to an internal
combustion engine wherein a supplementary
ignition system is provided for furnishing
ignition voltages during the starting period 60
of the engine, the arrangement is, in its pre-
ferred form, such that the ignition system
is started into operation at the time the sup-
ply of power is increased. We use a con-
troller for compelling the sequence of opera- 65
tions pointed out above, and in the preferred
arrangement, the controller is operated in a
single stroke from its inoperative position.
For instance, in the case of an electric start-
ing system, a normally open switch has a 70
succession of positions. In the first position,
the rotating members of the clutch are con-
nected by an electro-magnetically-operated
brake supplied with current from a battery.
In the same position or the next one, as de- 75
sired, the motor is supplied from the battery
with current limited by a resistance to an
amount sufficient for developing the small
torque required to turn the motor slowly to
take up the play in the gearing, but insuf- 80
ficient to start the engine from rest. In the
final position of the switch, full power for
the motor is supplied from the battery and
the supplementary ignition system is started
into operation with current from the bat- 85
tery. In all these positions, the flow of cur-
rent to the brake is maintained so that the
rotating members are connected during the
entire starting period.

The accompanying drawing illustrates the 90
preferred embodiment of our invention in
application, as an example, to an electric
starting system for an internal combustion
engine, wherein an over-running clutch is 95
included in the motor gearing. In this sys-
tem, the storage battery *a* has one terminal
grounded and the other terminal connected
to the central conducting segment *b* of a
foot switch suitable for use on an automobile 100
or motor boat. The switch shaft *c* carries
two conducting bridge members *d*₁, *d*₂ insu-
lated from each other and from the switch
shaft by the insulating material *e*. The
spring *f* tends to hold the switch shaft in 105
its open position, as shown. The segments
h and *i* are arranged in line so as to be en-
gaged by the bridge member *d*₁, whereas the
segments *k* and *l* are arranged in line on the

opposite side of segment *b* so as to be engaged by the bridge member *d*₂. The segment *h* is connected to the insulated terminal of the grounded winding *o* of the electromagnet *p*, whereas the segment *l* is connected through the resistance *m* to the segment *k* and also to the insulated terminal of the grounded series motor *n*. The segment *i* is connected to the supplementary ignition system embodying an electromagnetic interrupter *r* of high periodicity suitable for generating sparking voltages in the armature winding *s* of the magneto at each period of interruption of the mechanical inter-

rupter *x*.

The starting motor *n* drives the gear 14 which is meshed with the rotatable member 11 of the over-running clutch, the rotatable member 13 being permanently connected to the crank shaft 16 of the engine and being disengageably connected with the rotatable member 11 through the connecting element 12 carried by the rotatable intermediate member 10. This over-running clutch is similar in construction and operation to the one illustrated in Figs. 3 and 4 of Patent No. 1,259,876, issued March 19, 1918. In the construction shown herein, the brake 15 is applied to the member 10 when the winding *o* of the electromagnet *p* is energized, and when so applied, the connecting element 12 is moved into position to positively connect the two rotatable members 11 and 13.

The operation is as follows: In the position illustrated, the switch is open, the rotatable elements of the over-running clutch are disengaged, and a considerable amount of play or back lash exists in the gearing between the motor and the engine. In order to start the engine from rest, the operator depresses the switch shaft *c*. When the bridge members *d*₁, *d*₂ occupy the position shown in broken lines at I, current flows from the battery *a* through the segment *b* and bridge member *d*₁ to the segment *h* of the winding *o*, whereupon the electromagnet engages the brake 15 with the intermediate member 10 of the clutch and thereby causes the rotating members 11 and 13 of the over-running clutch to become positively connected and turn together as soon as the play in the gearing is taken up. When the switch reaches the second position shown in broken lines at II, the bridge member *d*₂ is in engagement with the segment *k*, and in addition to the current flowing to the winding *o* of the electromagnet, current also flows from the battery *a* through the resistance *m* to the motor *n*. The resistance *m* is so calibrated that the current flowing through it at that time starts the motor into slow rotation and develops sufficient torque to take up the play in the gearing between the motor *n* and the crank shaft 16 of the engine, but not sufficient torque to start the engine

from rest. For instance, if the switch is held in position II the motor will come to rest after the play has been taken up. However, the operator continues the stroke of the switch shaft *c* and finally depresses the bridge members *d*₁, *d*₂ to the position shown in broken lines at III. In this position the bridge member *d*₁ connects the segment *b* to both of the segments *h* and *i*, so that the electromagnet *p* still holds the brake 15 in engagement with the intermediate member 10 of the clutch, and the supplementary ignition system is started into operation by current from the battery. Also, the bridge member *d*₂ is engaged with the segment *l*, so that the motor *n* then receives full current directly from the battery instead of an amount limited by the resistance *m*. The motor then starts the engine from rest and brings it to a speed at which it develops its own power, the supplementary ignition system generating satisfactory ignition voltages to ignite the combustible mixtures drawn into the engine cylinders.

As soon as the speed of rotation of the engine shaft 16 exceeds the speed of rotation of the member 11, the connecting element 12 disconnects the clutch, whereupon the switch shaft *c* is released to its raised position, and all the circuits from the battery are interrupted. The notches *v*₁, *v*₂ and *v*₃ are engaged by the spring-pressed finger *u* to lightly hold the switch shaft at the three successive positions and to give an indication to the operator.

Inasmuch as the play in the gearing is entirely taken up in a part of a rotation of the motor, the member 11 of the clutch moves but slightly when the switch reaches position II. Thus, if desired, the segments *b* and *h* could be shorter, and the stroke of the shaft *c* decreased, or the segment *k* could be lengthened at the top, whereupon the positions I and II would be combined without the possibility of disengagement between the members of the clutch at the beginning of the initial starting period.

Having thus described our invention, what we claim is:

1. In engine starting apparatus, the combination with a starting motor, a source of power supply therefor, gearing including an over-running clutch between the engine and motor, and a brake engageable with the clutch to connect the rotating members thereof, of a controller which first causes the brake to engage the clutch and the starting motor to take up the play in the gearing, and then causes the flow of full power from the source of power supply to the motor to start the engine from rest.

2. In engine starting apparatus, the combination with a starting motor, a source of power supply therefor, gearing including an over-running clutch between the engine and

- motor, and a brake engageable with the clutch to connect the rotating members thereof, of a controller which first causes the brake to engage the clutch and the starting motor to take up the play in the gearing, and then causes the flow of full power from the source of power supply to the motor while maintaining the brake in engagement with the clutch.
- 10 3. In engine starting apparatus, the combination with a starting motor, a source of power supply therefor, gearing including an over-running clutch between the engine and motor, a supplementary ignition system for the engine, and a brake engageable with the clutch to connect the rotating members thereof, of a controller which first causes the brake to engage the clutch and the starting motor to take up the play in the gearing, and then causes the flow of full power from the source of power supply to the motor while simultaneously starts the supplementary ignition system into operation.
- 15 4. In engine starting apparatus, the combination with an electric starting motor, a source of power supply therefor, gearing including an over-running clutch between the engine and motor, electric connections including a resistance, and an electromagnetically-operated brake engageable with the clutch to connect the rotating members thereof, of a multi-position switch which first connects the winding of the electromagnet to the source of power supply to move the brake into engagement with the clutch and then connects the source of power supply to the motor through the resistance to take up the play in the gearing, and finally connects the source of power supply directly to the motor to start the engine from rest.
- 20 5. In engine starting apparatus, the combination with an electric starting motor, a source of power supply therefor, gearing including an over-running clutch between the engine and motor, electric connections including a resistance, and an electromagnetically-operated brake engageable with the clutch to connect the rotating members thereof, of a multi-position switch which first connects the winding of the electromagnet to the source of power supply to move the brake into engagement with the clutch and then connects the source of power supply to the motor through the resistance to take up the play in the gearing, and finally connects the source of power supply directly to the motor to start the engine from rest while maintaining the connection to the winding of the electromagnet and simultaneously connects the source of power supply to the supplementary ignition system to start it into operation.
- 25 In testimony whereof we affix our signatures.
- 30

AUGUST KAZENMAIER.
EUGEN BAUER.
